UNITED STATES PATENT OFFICE

DARWIN E. STEVENS AND CHARLES E. BROWN, OF DULUTH, MINNESOTA

DESIGN FOR A VIBRATING STOOL

Application filed May 14, 1931. Serial No. 39,858. Term of patent 7 years.

To all whom it may concern:

Be it known that we, DARWIN E. STEVENS and CHARLES E. BROWN, citizens of the United States, and residents of Duluth, in the county of St. Louis and State of Minnesota, have invented a new, original, and ornamental Design for Vibrating Stools, of which the following is a specification, reference being had to the accompanying drawing,

forming part thereof, in which, the figure is a perspective view of a vibrating stool showing our new design.

We claim:

The ornamental design for a vibrating stool as shown.

Dated, May 12th, 1931.

DARWIN E. STEVENS.
CHARLES E. BROWN.
